UNITED STATES PATENT OFFICE.

GEORGE V. DUMAS, OF CAMBRIDGE, MASSACHUSETTS.

MUSICAL INSTRUMENT.

1,100,422.

Specification of Letters Patent. Patented June 16, 1914.
Application filed June 20, 1913. Serial No. 774,797.

To all whom it may concern:

Be it known that I, GEORGE V. DUMAS, a citizen of the United States, and a resident of Cambridge, in the county of Middlesex and State of Massachusetts, have invented an Improvement in Musical Instruments, of which the following description, in connection with the accompanying drawings, is a specification, like characters on the drawings representing like parts.

This invention relates to musical instruments of the self-playing type employing perforated music sheets, and more particularly to the tracking devices by means of which the music sheet is maintained in its proper relation with the ducts in the tracker bar.

My invention will be best understood by reference to the following specification, when taken in connection with the accompanying drawings, showing two specific embodiments of my invention, while its scope will be more particularly pointed out in the appended claims.

25 In the drawings: Figure 1 is a plan of a music sheet tracking mechanism for musical instruments embodying my invention, the top of one of the bellows being partly broken away to disclose the duct openings therein; Fig. 2 is a front elevation of the same, also with the bellows partly broken away and shown in section to disclose the ducts; Fig. 3 is a detail sectional view on line 3—3 of Fig. 2, looking toward the left; Fig. 4 is a detail plan section, partly broken away, on an enlarged scale on line 4—4 of Fig. 2; Fig. 5 is a detail plan section of a modification of the parts shown in Fig. 4; Fig. 6 is a front elevation of some of the parts shown in Fig. 1, showing the relation of the sheet to the two tracking controlling openings, while the instrument is being played; and Fig. 7 is a detail sectional view on line 7—7 of Fig. 6.

40 In musical instruments employing perforated music sheets traveling over note-operating openings in a tracker bar, there are usually provided devices co-operating with and governed by the sheet, to insure a proper registration of the note perforations in the sheet with the corresponding note-operating openings in the tracker bar. In the operation of all such musical instruments, much difficulty has been experienced heretofore, because of the fact that the various climatic and weather conditions have caused the

sheet to swell, or shrink, and its width to vary to such an extent as to affect more or less seriously the operation of the tracking devices.

My invention relates to mechanism by means of which the tracking controlling openings, or other devices, are shifted laterally with relation to the note-playing openings to compensate for changes in width of the music sheet, due to any cause. In one type of mechanisms of this class, two openings are provided in the tracker bar, one for each edge of the sheet, and any tendency of the latter to shift laterally so that its note-operating perforations would be moved out of alinement with the note-playing openings in the tracker bar is counteracted by pneumatic devices under the control of these openings, the edges of the sheet constituting valves to open or close, or vary the area of the openings. In another type of mechanism, a finger or fingers, engaging the edges of the music sheet, operate suitable devices to control the tracking of the music sheet.

My invention is not limited in its application to musical instruments having tracking devices of any particular type, but in the embodiment of my invention which I have selected as an illustrative example, the tracking or shifting of the sheet is under the control of devices including a duct or opening adjacent one edge of the sheet. In the operation of devices of this particular type, any tendency of the sheet to shift laterally is counteracted by mechanism rendered effective by the uncovering of the opening by the edge of the sheet.

Referring to the drawings, and to the embodiment of my invention which I have selected for illustrative purposes, I have there shown a portion of an automatic musical instrument of the described type, comprising a perforated music sheet 8 of familiar form, carried by a music sheet winding roll 9 and a music spool 10, across a track bar 11. The latter is herein supported on uprights 13 and 14, and is provided as usual with a series of note-playing openings, or ducts, 15, one for each note of the instrument. The winding roll 9 and music spool 10 are herein rotatably mounted in a well known manner at one pair of ends, in bearing members 16 and 17, mounted to move axially in bearings 18 and 19 in the upright 13, and having springs 20 and 21 of usual form and ar-

angement urging the bearing members, and music rolls carried thereby, toward the right (Fig. 2). The other ends of the music roll and music spool are clutched to and driven by shafts 22 and 23, respectively, the latter being journaled in bearings 24 and 25 in the upright 14, and bearings 26 and 27 in a frame 28. The shafts 22 and 23 may be driven by any appropriate mechanism, which 10 it will be unnecessary here to describe, it being understood, however, that during the playing of the instrument, the music roller 9 is rotated in the proper direction to cause the music sheet to travel across the tracker 15 bar in the usual and well known manner.

The outer, or right-hand, ends of the shafts 22 and 23 are engaged, respectively, by arms 29 and 30 secured to an upright rock-shaft 31, the latter being mounted to 20 turn at its upper and lower ends in bearings 32 and 33 in the frame 28. Secured to the rock-shaft 31 is an arm 34, to which is pivoted one end of a link 35, the latter being pivoted at its other end to an arm 36 formed 25 on, or secured to, a rock-shaft 37, the latter being mounted in suitable bearings on the upright 13. The rock-shaft 37 is herein provided with another arm 38, connected by a link 39 to a movable wall 40 of a bellows 30 41, which acts through the connections just described to shift the music rolls axially against the tension of their springs, and consequently shifts the music sheet with relation to the tracked bar.

35 In the form of my invention illustrated in Figs. 1, 2, 4, 6 and 7, there is provided adjacent the right-hand edge of the sheet a sheet-controlling opening, or duct, 42, formed in a member 43 slidably mounted in 40 the upright 14, and constituting in effect a movable continuation, or extension, of the tracker bar 11. The sheet-controlling duct, however, need not be placed in a continuation of the tracker bar, but if desired, may 45 be placed above or below the latter, and in Fig. 5, I have shown a slight modification in which, a tubular member 44, provided with a controlling duct 45, is mounted to slide in a suitable bearing 46 in the upright. 50 In either case, the duct is connected to the bellows 40 by appropriate connections, herein including a flexible conduit 47 and a conduit 48, to a duct 49 having an opening 50 communicating with the interior of the bellows 40. The latter may be exhausted by any appropriate means, but herein is provided with a minute exhaust passage 51, connected by a duct 52 to a flexible conduit 53, which latter in practice will be connected to 55 the usual wind chest of the musical instrument. When the operator commences to operate the foot bellows, air will at once be exhausted from the bellows 41, whereupon the latter will begin to collapse. It 60 will be observed that the exhaust passage

51 leading from the bellows 41 is substantially smaller in area than the passages leading from the bellows to the duct 42 at the edge of the music sheet. Because of this difference in areas, when the music sheet 70 for any reason shifts toward the left and commences to uncover the duct 42, atmospheric air will rush through the described conduits to the bellows 41 faster than the air is exhausted therefrom, the result being 75 that said bellows will commence to open, and will act through the described connections to shift the music rolls toward the right, until the edge of the music sheet once more covers the duct 42. In an 88 note 80 player, the note-operating openings in the tracker bar are placed very close to each other, the space between them in practice being about one-thirty-second of an inch. It will be evident that, since the relation 85 of the music sheet to the note-operating openings is governed by the sheet-controlling opening 42 at one edge of the sheet, if the latter should swell or shrink to any great extent, the perforations or slots in 90 the music sheet, particularly those most remote from the opening 42, would not properly register with the corresponding note-operating openings in the tracker bar. In half the width of the music sheet, however, 95 there is not sufficient swelling or shrinking to cause any defect in the placing of the notes. Consequently, if the longitudinal median line of the sheet were to be maintained at all times in exact alignment with 100 a point midway of the two ends of the tracker, all of the notes of the instrument would be sounded correctly. To this end, therefore, I provide at the left-hand edge of 105 the sheet a duct 54 similar to the duct 42, and provide suitable means under the control of the left-hand duct simultaneously to shift both ducts laterally equal distances with relation to the note-operating openings. 110

In the form of my invention shown in Fig. 4, the duct 54 is formed in a member 55, similar to the member 43 already described, and constituting in effect a continuation or extension of the tracker bar 11. In 115 the form shown in Fig. 5, a duct 56 adjacent the left-hand edge of the sheet is formed in a tube 57, similar to the tube 44 already described, and mounted to slide axially. Referring to the form shown in Fig. 4, the 120 slides 43 and 55 may be slidably mounted upon the tracker bar 11 in any other suitable manner, but herein the latter is provided with longitudinal slots 58 and 59, and the slides 43 and 55 are provided, respectively, with tongues 60 and 61, guided by said slots. Herein, the slides are held in place in their respective slots by plates 62 and 63, secured to the backs of their respective slots by screws 64 and 65. 125 130

Referring to the modification shown in Fig. 5, the tubes 44 and 57 may be guided in the uprights or supports of the tracker bar, and may also be guided by a rod 66, having a sliding fit in the adjacent ends of the tubes. The latter may be closed at their inner ends by plugs 67 and 68, and at their outer ends by plugs 69 and 70 fitted therein.

The slides 43 and 55 of the form shown in Fig. 4, or the slides 44 and 47 of the form shown in Fig. 5, may be connected to each other by any appropriate mechanism to cause them simultaneously to move in opposite directions, but herein the slide 43 is pivotally connected to a lever 71, fulcrumed at 72, and a slide 55 is pivotally connected to a lever 73 fulcrumed at 74, the upper ends of these levers being pivoted respectively to links 75 and 76, which latter are pivoted at their inner ends to crank pins 77 and 78 carried by a crank disk 79. Herein, the latter is secured to a rock-shaft 80, journaled in suitable bearings in a bracket 81 secured to a horizontal support 82, which latter joins the uprights 13 and 14. The slides 43 and 55 may be drawn toward each other by any suitable means, but herein a spring 83, secured at one end to the link 76 and at its other end to the horizontal support 82, constantly tends to move said slides toward their innermost position.

The duct, or opening, 54 in the slide 55 is connected to a suitable bellows 84 by appropriate connections, including a flexible conduit 85 and a conduit 86, to a duct 87 having an outlet 88 opening into the interior of the bellows 84. Air may be exhausted from the latter through an exhaust passage 89, communicating, through the duct 52 and conduit 53 already described, with the wind chest of the instrument. The bellows 84 is provided with a movable wall 91 connected by a link 92 to an arm 93, the latter being suitably formed on, or secured to, a rock-shaft 94 mounted in suitable bearings 95. To this rock-shaft is also secured an arm 96, connected by a link 97 with an arm 98, the latter being secured to the rock-shaft 80 hereinbefore described. Just as soon as the usual pumping bellows of the instrument are operated, the air is exhausted from the interior of the bellows 84, and the latter commences to collapse, thus acting through the described connections to move the slides 43 and 55, with their ducts 42 and 54, away from each other, and such movement will continue until these ducts commence to be uncovered by the edges of the music sheet, whereupon atmospheric air will rush into the duct 54 and through the described conduits to the bellows 84. Since the exhaust passage 89 is smaller than the passages leading to the duct 54, air will be admitted to the bellows 84 faster than it is exhausted from the exhaust passage 89, with the con-

sequence that the closing movement of the bellows will at once cease. The bellows may be supported in any other suitable manner, but herein they have in common a fixed wall 99, supported by posts 100 upon a horizontal member 101 forming a part of the player action frame.

Having thus specifically described the tracking mechanism, I will now describe its general operation: The person operating the instrument first hooks the end of the music sheet onto the music winding roll 9 in the usual manner, and then commences to operate the pedals, whereupon the mechanism will operate in the usual manner to wind the music sheet onto the winding roll 9. As soon as the music sheet covers the ducts 42 and 54, the supply of atmospheric air to the bellows 41 and 84 is cut off, and the latter begin to collapse, owing to the fact that they are in communication with the wind chest from which air is being exhausted. The bellows 41 and 84 will continue to collapse until the one has shifted the music sheet, and the other has shifted the ducts 42 and 54 to a point where the latter begin to be exposed at the edges of the music sheet. This having occurred, atmospheric air will rush into these ducts, and further collapsing movement of both bellows will cease. It will now be evident that any narrowing or widening of the sheet, or any shifting of the latter toward the one side or the other, will cause the ducts 42 and 54 to be shifted toward or away from each other, or cause the sheet to be shifted from right to left, or from left to right as the case may be, with the result that during the playing of the music, the longitudinal median line of the sheet will at all times be maintained in exact alignment with a point midway between the two middle note-operating openings of the tracker bar. Therefore, no matter what the climatic or weather conditions may be, and regardless of the changes in width of the sheet from time to time, the described mechanism will compensate for such changes in width of the music sheet, and will at all times maintain the latter in its proper relation with the note-operating openings in the tracker bar, without any attention on the part of the operator.

While I have herein shown and described two specific forms, or embodiments, of my invention for illustrative purposes, and have disclosed and discussed in detail the construction and arrangement incidental to two specific applications thereof, it is to be understood that the invention is limited neither to the mere details or relative arrangement of parts, nor to its specific embodiments herein shown, but that extensive deviations from the illustrated forms or embodiments of the invention may be made, without departing from the principles thereof.

Having thus described my invention, what I claim and desire by Letters Patent to procure is:—

1. A musical instrument having a series of note-operating openings, music sheet tracking means having a tracking opening coöperating with one edge of the sheet, and means having a single opening coöperating with the other edge of the sheet for automatically shifting both openings in opposite directions laterally with respect to the note-operating openings to compensate for changes in width of the music sheet.
2. A musical instrument having a series of note-operating openings; music sheet controlling means including devices coöperating with the music sheet adjacent its edges, and means controlled by the coöperative action of the music sheet and one only of said devices to cause both of the latter to be shifted in opposite directions, respectively laterally with respect to the note-operating openings.
3. A musical instrument having a series of note-operating openings, music sheet tracking means having a single device coöperating with one edge of the sheet, and means having a single device coöperating with the other edge of the sheet for automatically shifting both devices in opposite directions, respectively, laterally with respect to the note-operating openings to compensate for changes in width of the music sheet.
4. A musical instrument having a series of note-operating openings, and means having only a single opening coöperating with one edge of the sheet for automatically shifting said single opening with respect to the note-operating openings to compensate for changes in width of the music sheet.
5. A musical instrument having a series of note-operating openings, two music sheet controlling openings coöperating with opposite edges, respectively, of the music sheet, means including a bellows communicating
- with one of said sheet controlling openings for tracking the music sheet, and means including a bellows communicating with the other opening for automatically shifting both of said sheet-controlling openings in opposite directions, respectively, and means connecting said sheet-controlling openings to enforce their simultaneous movement.
6. A musical instrument having a series of note-operating openings, two music sheet controlling openings coöperating with opposite edges, respectively, of the music sheet, means including a bellows communicating with one of said sheet-controlling openings for tracking the music sheet, means including a bellows communicating with the other sheet-controlling opening for automatically shifting said sheet-controlling openings outwardly away from each other, and yielding means normally tending to move said sheet-controlling openings toward each other.
7. A musical instrument having a row of note-operating openings, two music sheet controlling openings coöperating with opposite edges, respectively, of the music sheet, yielding means tending to move the music sheet in one direction longitudinally of the row of note-operating openings, means including a bellows communicating with one of said sheet controlling openings for moving the music sheet in the opposite direction, means including a bellows communicating with the other sheet-controlling opening for automatically shifting said sheet controlling openings outwardly away from each other, and yielding means normally tending to move said sheet-controlling openings toward each other.

In testimony whereof, I have signed my name to this specification, in the presence of two subscribing witnesses.

GEORGE V. DUMAS.
